CLAIM

The ornamental design for an auxiliary catamaran trampoline, as shown and described.

DESCRIPTION

FIG. 1 is an inverted rear elevational view of an auxiliary catamaran trampoline showing my invention.

FIG. 2 is a top plan view of my invention.

FIG. 3 is a side elevational view of my invention, the right side being a mirror image of the left side.

FIG. 4 is a front elevational view of my invention.

FIG. 5 is a bottom plan view of my invention.

Fig. 1.

Fig. 2.

Fig. 3.

Fig. 4.

Fig. 5.
